UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 17,858, dated November 1, 1887.

Application filed September 21, 1887. Serial No. 250,351. Term of patent 3½ years.

To all whom it may concern:

Be it known that I, JENNIE SHEILS, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by the pattern will appear.

The design shows a basque and a round walking-skirt. The skirt exhibits a full left drapery extending from the right side of the front across the left side to the center of the back, and displaying kilt-plaits at the front and sides and a high full draping at the center of the back, and a full right drapery that overlaps the left across the front and exhibits

irregular jabot folds in front, kilt-plaits at the sides, and a high draping at the center of the back, the outline of the right drapery being rounding at the front and back, and both draperies descending nearly to the edge of the skirt. The basque describes a deep point at the center of the front and back, a high arch at the sides, is close-fitting, and displays a low V-shaped neck both back and front.

What I claim as my invention, and desire to secure by Letters Patent, is—

The design for a lady's costume, as shown in the engraved prints accompanying this specification.

JENNIE SHEILS.
